FRANK W. MERRICK, OF BOSTON, MASSACHUSETTS, ASSIGNOR TO UNION LOCK STITCH COMPANY, OF BOSTON, MASSACHUSETTS, A CORPORATION OF MAINE.

LASTING-MACHINE.

1,324,403.

Specification of Letters Patent.

Patented Dec. 9, 1919.

Application filed April 24, 1916. Serial No. 93,049.

To all whom it may concern:

Be it known that I, FRANK W. MERRICK, a citizen of the United States, residing at Boston, in the county of Suffolk, State of Massachusetts, have invented a certain new and useful Improvement in Lasting-Machines, of which the following is a specification, reference being had therein to the accompanying drawings.

10 The invention has relation to gripper-mechanisms such as are employed in operating upon leather and the like, more particularly in the processes of boot and shoe manufacture. Also, to the combinations of 15 which gripper-mechanisms constitute elements in pulling-over-machines and other machines employed in performing or furthering lasting.

20 Stated in general terms, the invention comprises improved gripper-mechanism in which pulling-over or other clamps or grippers are actuated by fluid-pressure so as to close them upon a piece of leather, as for example marginal portions of a shoe-upper, 25 and keep them closed while stretching or pulling is effected and, for instance, until the upper or other piece of leather has been secured in place. I prefer to employ an elastic fluid-pressure medium, although I 30 contemplate the employment of oil or water in some instances in which resilient action is not needed. The invention comprises, also, improvements in the mode and means of mounting the gripper-devices of gripper-mechanisms such as aforesaid.

A convenient illustrative embodiment of the various features of the invention is shown in the drawings, in which latter,—

Figure 1 shows in elevation opposite sets 40 of pulling-over gripper-devices including fluid-pressure actuating means, and in connection with the said gripper-devices a last-support, a last with certain parts of a shoe thereon, and a device constituting a de- 45 pressor and hold-down.

Fig. 2 is a plan view of the parts which in Fig. 1 are represented below the plane indicated by the dotted line 2, 2, in the latter figure.

50 The illustrative embodiment aforesaid is adapted for employment for pulling-over purposes in connection with lasting machines on the order of that shown and described in Letters Patent No. 1,245,117, granted under date of October 30, 1917,

upon my application therefor filed April 28, 1913, Serial No. 764,005.

The depressor and hold-down 1 with its downwardly projecting pins 1^a, 1^a, as also the support or mounting 2 for the last 3 to 60 which the upper 4 and insole 5 of a shoe are applied, are or may be constructed, arranged, and combined with associated parts and devices to operate in practice substantially as in the case of corresponding parts 65 in my Letters Patent aforesaid.

Briefly stated, the last-support 2 is yieldingly supported vertically, and the depressor and hold-down 1 is mounted with capacity for vertical movement so as to enable it to be moved downward from the elevated position which it normally occupies, so as in its descent to carry the ends of the pins 1^a, 1^a, into contact with the insole 5 that has been applied to the bottom of the 75 last 3, and by the continued descent press the last and last-support downward. The said depressor and hold-down has combined therewith actuating mechanism and controlling devices by means of which at the 80 will of the operator, it is actuated vertically and is caused to descend, or to rise again, or to dwell either at an intermediate point in its descent or ascent, or in the lowest position, or in upwardly retracted position. 85 Depression of the last and last-support carries the last and the upper thereon downward relative to the pulling-over grippers 6, 7, 6, 7, etc. In practice, prior to the depression of the last and last-support, the 90 margins of the upper are to be engaged as shown in Figs. 1 and 2 of the drawings hereof by the said grippers, so that in consequence of the said margins being engaged and held by the grippers the depression of 95 the last relative to the grippers will strain and stretch the upper around the last.

As indicated at the outset herein, the first portion of the invention is concerned more particularly with means for automatically 100 closing the grippers upon the leather and keeping them closed so as to maintain their hold upon the engaged portions of the leather while the upper is being pulled into position about the last. The specific construction of the grippers themselves, and their more immediate mechanical connections, and the means and manner of mounting the grippers, may vary in practice. 105 Herein the gripper-members 6, 6, they hav- 110

ing downwardly-extending jaw-portions, are provided upon the inwardly-extending upper extremities of upstanding arms 6^a, 6^a, located at opposite sides of the last-support. 5 The gripper-members 7, 7, are mounted pivotally at 7^a, 7^a, upon the upper portions of the arms 6^a, 6^a, with their jaw-portions in convenient working relations with those of the gripper-members 6, 6. For the purpose 10 of transmitting the required movements to the gripper-members 7, 7, the latter are provided with outwardly-extending arms which have connected pivotally to the same at 7^b, 7^b, the upper ends of links or connecting-rods 7^c, 7^c, which last at their lower ends are connected pivotally at 7^d, 7^d, to operating levers 7^e, 7^e. The said levers are mounted pivotally at 7^f, 7^f, upon the lower portions of the arms 6^a. When movement is given 15 to the respective levers 7^e, 7^e, through power applied thereto, the movable gripper-members 7, 7, of the respective pairs of grippers are operated to open and close. The power by which the grippers are held normally in 20 open condition, and by which the opening of the grippers from their closed condition is effected when such opening is permitted, is applied by means of contracting spiral springs 8, 8, each connected at one end, as 25 at 8^a, to an operating lever 7^e, and connected at the other end, as at 8^b, to a convenient portion of one of the fixed arms 6^a. Normally, the movable jaws of the gripper-members 7, 7, are held separated from the 30 jaws of the stationary gripper-members 6, 6, by the tension of the said springs. In carrying the first portion of the invention into effect, the effect of the fluid-pressure is transmitted to the operating levers 7^e, 7^e, 35 40 to close the grippers upon the portions of leather with which they are to engage, and keep them closed thereon.

The fluid-pressure gripper-operating means comprises essentially a cylinder 9 and 45 contained piston 10 for each clamp or pair of gripper-members. An outward projection 10^a from the piston 10 engages with the operating lever 7^e of the corresponding pair of gripper-members, so that when the piston 50 is moved in one direction, by pressure of the pressure-applying-medium that is admitted to the cylinder, the said operating lever 7^e is swung in the direction to transmit a closing movement to the movable 55 gripper-member of the said pair of grippers, and the grippers are held closed so long as the pressure is maintained within the cylinder. Tubes or pipes for conveying the pressure-transmitting-medium to the cylinders 60 are shown at 11, 11. Manually-controlled valve-devices (not shown) are employed in practice for controlling the pressure within the respective cylinders.

Preferably, compressed air is employed as 65 a pressure-transmitting-medium, although

steam or gas may be employed. All three, namely, compressed air, steam, or gas, give an elastic action. In some cases in which elastic action is not required I may utilize oil or other liquid.

The means of controlling the application of pressure at the will of the operator may vary. The valves for that purpose may be of any approved character, and be arranged and operated as may be found most convenient in practice.

In the use of the illustrated embodiment of the invention, after the last 3 has been inserted into the upper 4 that is to be lasted thereon, and after the necessary preliminary 70 adjustments have been made, the upstanding margins of the upper are placed between the jaws of the respective pairs of grippers, and then, by admitting the pressure into the cylinders the grippers are closed upon the 75 said margins. While the grippers are thus closed upon and holding the upstanding margins of the upper, the depressor and hold-down 1 is caused to move downward 80 so that its downwardly-extending pins 1^a, 1^a, 85 take bearing against the sole of the last, or against the insole 5 applied to the last. By the continued descent of the depressor and hold-down the last and last-support are pressed downward so that the last is pressed 90 down within the upper and the latter stretched and pulled into position about the last. In the drawings, the grippers are shown engaged with the upper at opposite 95 points in connection with the waist of the 100 last and shoe, and also at opposite points in connection with the foreparts of the last and shoe. The number of grippers and the location thereof may vary in practice as desired or found necessary.

One feature of the invention consists in mounting the respective pairs of grippers with capacity to swivel transversely upon vertical axes, so that the jaws of a pair may conform their position to the direction in 110 which the adjacent portion of the last-margin extends. This capacity is secured by supporting the arms 6^a in manner permitting them to turn upon the said vertical axes. For convenience in construction and 115 in providing for maintaining working relations between the pressure-devices and the transmitting levers 7^e, the pressure-cylinders 9 are mounted to turn transversely in unison with arms 6^a. Conjoint turning movement of a pair of grippers, its supporting arm, and the corresponding pressure-devices, is provided for in the illustrative embodiment by affixing the base of the supporting-arm 6^a by means of a bolt 6^b to a lug 12^b, 10^b rising from the top of the cylinder 10, and combining the cylinder-base 10^c with the fixed support 10^d by means of a vertical pivot 10^e. This pivot permits the cylinder, arm, and pair of grippers to swivel hori- 125 130

zontally so as to conform the faces of the gripper-jaws to the direction of the adjacent portion of the margin of the last. A slot 6^c in the base of the arm 6^a, occupied by the stem of bolt 6^b, provides for vertical adjustment of the arm so as to enable the gripper-jaws to be located at the desired height.

Each cylinder is mounted by means of a horizontal pivot 10^c upon its base 10^a. This pivot enables the corresponding pair of grippers to be swung toward and away from the position of the last-support and last. This capacity for inward and outward swinging movement enables the grippers to be swung back entirely away from and clear of the last-support and last, when desired, and to be swung inward toward the last into proper position for engagement with the different portions of the upstanding margin of the upper.

A further feature of invention consists in a provision whereby as the last is depressed relative to the pulling-over grippers so that the upper is caused to fit the last, the said grippers are made to draw the side portions of the upper by an automatic action snugly inward against and around the sides of the last, and to lap them inwardly over the bottom of the last in proper position and relations for being secured in place. To this end, the pivots 10^c, 10^c, are located at some distance beyond the last-support and last at either side of these latter, as shown in Fig. 1, so that the grippers swing upon axes set out or outstanding beyond the last, at opposite sides of the latter. The upper portions of the gripper-supporting arms 6^a, 6^a, extend inwardly toward the last-support and last so that the grippers overhang inwardly relative to the said pivotal axes. The result in operation is that as the last is caused to descend the downward pull of the side-portions of the upper upon the grippers acts with a tendency to swing the grippers inwardly above the last, so as to carry the said side-portions inward toward the middle line of the last as in Fig. 1.

As described herein with reference to the drawings, the relative movement by which the pulling-over action is produced is due to vertical shift of the last and last-support. Except as hereinafter indicated otherwise in the claims, it is equally adapted to be secured by shift of the gripper-mechanism.

Pneumatically-operated clamps or grippers have important advantages over mechanically and positively or spring-actuated clamps or grippers. No matter how the thickness of the leather may vary, a pneumatically-operated clamp or pair of grippers will grip the material with the same pressure and with the same effect. A positively actuated clamp or pair of grippers if set to grip a thick piece of leather will not

hold a thin piece, and if set to hold a thin piece will tear or crush a thick piece. Hence the results will be unsatisfactory or injurious in the case of variations in thickness. The results are objectionable with a spring-operated clamp or pair of grippers also; with an increase in the thickness of the material grasped, the gripper-members or jaws grip or bite with greater tension with a likelihood of injury. With pneumatically-operated devices, the pressure upon the material between the jaws or gripping members merely corresponds with the fluid-pressure within the cylinder, and hence injurious results do not follow when an increase of thickness of material is presented, and an effective hold will always be taken notwithstanding a smaller thickness of material is grasped. The importance of the invention resides largely in the fact that leather constantly varies in thickness, consistency, and resiliency. Some leather is soft and tough; some is hard and brittle; some is dead and inert; some is more or less elastic; some is like putty and will not recover after being subjected to a pull or strain. Consequently, a clamp or pair of grippers set to operate upon one grade and thickness of leather and actuated positively or by spring-tension will not operate satisfactory on any other grade or thickness. A spring-operated clamp or pair of gripping members depends upon the right adjustment of the spring-tension to suit the material which is to be operated upon. There can be only one proper relation; there can be only one thickness and consistency of leather upon which any given setting of the spring will be satisfactory. Hence, with material constantly varying, as occurs in practice, entirely satisfactory results cannot be attained when spring-tension is depended upon. With a pneumatically-operated clamp or pair of grippers the pressure of the jaws upon the material being operated upon, whatever may be the thickness of such material, always is equal to the pressure within the operating cylinder, and never is greater nor less.

What is claimed as the invention is,—

1. Pulling-over mechanism comprising a pair of grippers adapted to receive between them and to engage with a margin of a shoe-upper, a support for the said pair of grippers, a removably-mounted last-support, and means for producing movement of the said last-support relative to the said pair of grippers to effect pulling-over, said pair of grippers having combined therewith fluid-pressure means for closing them upon the said margin.

2. Pulling-over mechanism comprising a pair of grippers adapted to receive between them and to engage with a margin of a shoe-upper, a support for the said pair of grippers, a movably-mounted last-support, and

means for producing movement of the said last-support relative to the said pair of grippers to effect pulling-over, said pair of grippers having combined therewith pneumatic 5 means for closing them upon the said margin.

3. In pulling-over mechanism, the combination comprising a last-support, a pulling-over clamp or pair of grippers, a support for 10 said clamp or pair of grippers adapted to swivel upon a vertical axis to permit the position of the clamp-jaws or gripper-members to correspond with the direction of the adjacent portion of the side of the last, and 15 also mounted to swing transversely relative to the last upon a pivotal axis which is set out or outstanding beyond the last, the said grippers overhanging inwardly relative to said pivotal axis, and adapted to be swung 20 inwardly by the pull of the upper during the pulling-over action so as to carry the side-portions of the upper inward toward the middle line of the last, and fluid-pressure means for closing the clamp or pair of 25 grippers and keeping the same closed.

4. In pulling-over mechanism, the combination comprising a last-support, a pulling-over clamp or pair of grippers, a support for 30 said clamp or pair of grippers adapted to swivel upon a vertical axis to permit the position of the clamp-jaws or gripper-members to correspond with the direction of the adjacent portion of the side of the last, and 35 also mounted to swing transversely relative to the last upon a pivotal axis which is set out or outstanding beyond the last, the said grippers overhanging inwardly relative to said pivotal axis, and adapted to be swung 40 inwardly by the pull of the upper during the pulling-over action so as to carry the side-portions of the upper inward toward the middle line of the last, and fluid-pres-

sure means for closing the clamp or pair of grippers and keeping the same closed, including a pressure-cylinder mounted upon 45 the said support for the clamp or pair of grippers.

5. In pulling-over mechanism, the combination comprising a last-support, and pulling-over grippers mounted to swing transversely upon pivotal axes which are set out or outstanding beyond the last, the said grippers overhanging inwardly relative to the said pivotal axes and swung inwardly by the pull of the upper during the pulling-over action so as to carry the side-portions of the upper inward toward the middle line of the last, and the last-support and the grippers arranged for relative vertical movement to effect pulling-over. 50 55 60

6. In pulling-over mechanism, the combination comprising a last-support, pulling-over grippers, and gripper-supports swinging transversely upon pivotal axes which are set out or outstanding beyond the last 65 having gripper-supporting arms extending inwardly toward the last-support and last so that the grippers overhang inwardly relative to the said pivotal axes and are swung inwardly by the pull of the upper 70 during the pulling-over action so as to carry the side-portions of the upper inward toward the middle line of the last. said supports also adapted to swivel upon vertical axes, and the last-support and the grippers 75 arranged for relative vertical movement to effect pulling-over.

In testimony whereof I affix my signature in presence of two witnesses.

FRANK W. MERRICK.

CHAS. F. RANDALL,
ELLEN O. SPRING.

It is hereby certified that in Letters Patent No. 1,324,403, granted December 9, 1919, upon the application of Frank W. Merrick, of Boston, Massachusetts, for an improvement in "Lasting-Machines," an error appears in the printed specification requiring correction as follows: Page 3, line 119, claim 1, for the compound word "removably-mounted" read *movably-mounted*; and that the said Letters Patent should be read with this correction therein that the same may conform to the record of the case in the Patent Office.

Signed and sealed this 6th day of January, A. D., 1920.

[SEAL.]

M. H. COULSTON,
Acting Commissioner of Patents.
